[57] CLAIM

The ornamental design for a surgical support stand for use in arthroscopic surgery of the shoulder or the like, as shown and described.

DESCRIPTION

FIG. 1 is a front, top and left side perspective view of a surgical support stand for use in arthroscopic surgery of the shoulder or the like showing our new design;

FIG. 2 is a front elevational view thereof;

FIG. 3 is a left side elevational view thereof;

FIG. 4 is rear elevational view thereof;

FIG. 5 is a right side elevational view thereof;

FIG. 6 is a top plan view thereof;

FIG. 7 is a bottom plan view thereof; and

FIG. 8 is a front elevational view showing the surgical support stand for use in arthroscopic surgery of the shoulder or the like in an alternate position of adjustment.

FIG. 5

FIG. 4

FIG. 6

FIG. 7

FIG. 8
